(57) **CLAIM**

I claim the ornamental design for a motor housing with electronics housing, as shown and described.

DESCRIPTION

FIG. 1 is a top perspective view of a motor housing with an electronics housing showing the new design.

FIG. 2 is a top view thereof.

FIG. 3 is a bottom view thereof.

FIG. 4 is a left side view thereof.

FIG. 5 is a right side view thereof.

FIG. 6 is a front view thereof.

FIG. 7 is a rear view thereof.

FIG. 8 is a bottom perspective view thereof.

FIG. 9 is a top perspective view of an electronics housing of FIG. 1 showing the new design.

FIG. 10 is a top view thereof.

FIG. 11 is a bottom view thereof.

FIG. 12 is a front view thereof.

FIG. 13 is a rear view thereof.

FIG. 14 is a right side view thereof.

FIG. 15 is a top perspective view of a shroud portion of the motor housing of FIG. 1 showing the new design.

FIG. 16 is a top view thereof.

FIG. 17 is a bottom view thereof.

FIG. 18 is a front view thereof.

FIG. 19 is a rear view thereof.

FIG. 20 is a right side view thereof.

FIG. 21 is a top perspective view of a mounting portion of the motor housing of FIG. 1 showing the new design.

FIG. 22 is a top view thereof.

FIG. 23 is a bottom view thereof.

FIG. 24 is a front view thereof.

FIG. 25 is a rear view thereof; and,

FIG. 26 is a right side view thereof.

The broken lines shown illustrate the portions of the motor housing with electronics housing that form no part of the claimed design.

1 Claim, 26 Drawing Sheets
